UNITED STATES PATENT OFFICE.

HANS BULL, OF PHILADELPHIA, PENNSYLVANIA.

PROCESS FOR THE SULFONATION OF AROMATIC HYDROCARBONS OR THEIR DERIVATIVES.

1,247,499.

Specification of Letters Patent. Patented Nov. 20, 1917.

Application filed September 2, 1916. Serial No. 118,185.

To all whom it may concern:

Be it known that I, HANS BULL, a subject of the King of Norway, and a resident of the city and county of Philadelphia, State 5 of Pennsylvania, have invented a certain new and useful Process for the Sulfonation of Aromatic Hydrocarbons or Their Derivatives, of which the following is a specification.

10 My invention relates to a process for the continuous or intermittent sulfonation of aromatic hydrocarbons or their derivatives, accompanied by simultaneous extraction of the sulfonated product and has as its object 15 an efficient and expeditious method for economically performing said operation.

In the following I have described, in connection with the accompanying drawings, a way of carrying out my process with a 20 modification thereof, the principles of the invention being more particularly set forth hereinafter in the claims.

The drawings are diagrammatic representations of certain forms of apparatus adapted for use in connection with the practice 25 of the process, Figure 1 showing a single receptacle with suitable connections and Fig. 2 a plurality of receptacles connected in series.

30 Similar numerals of reference indicate similar parts throughout the several views.

In Fig. 1, the receptacle is indicated by the numeral 1, 2 and 3 indicate the respective inlet pipes or connections, and 4 and 5 35 the respective outlet pipes or connections. Said pipes or connections may be suitably valve controlled as desired.

In Fig. 2, 6, 7, 8, 9 and 10 indicate tanks or receptacles preferably arranged one above 40 the other, so that they may be discharged by gravity serially from one to the other downward. 11 indicates a pipe entering tank 10 at preferably a little above the middle portion. 12 is a pipe leading from the bottom of tank 10 to preferably a little 45 above the middle of tank 9. 13 is a pipe leading from the bottom of tank 9 preferably a little above the middle of tank 8. 14 is a pipe leading from the bottom of tank 8 to preferably a little above the middle of tank 7. 15 is a pipe leading from the bottom of tank 7 to preferably somewhat 50 above the middle of tank 6. 16 is a discharge pipe from the bottom of tank 6.

Pipes 11, 12, 13, 14, 15 and 16 are all suitably valve controlled. 55

17 is a pipe entering tank 6 near its bottom. 18 is a pipe leading from near the top of tank 6 to near the bottom of tank 7. 19 is a pipe leading from near the top of tank 7 to near the bottom of tank 8. 20 is a pipe leading from near the top of tank 8 to near the bottom of tank 9. 21 is a pipe leading from near the top of tank 9 to near the bottom of tank 10 and 22 is a discharge 60 pipe from near the top of tank 10.

The process is not restricted to the sulfonation of any particular aromatic hydrocarbon or derivatives of the same nor to the use of any particular solvent therefor provided 70 the solvent possesses the following properties. 1. That sulfuric acid of the strength used in the sulfonation is not appreciably soluble therein. 2. That the solvent be of lower specific gravity than said sulfuric 75 acid. 3. That the aromatic hydrocarbon or its derivative to be sulfonated be soluble in the solvent. 4. That the product of sulfonation be soluble in the solvent.

As illustrations of aromatic hydrocarbons 80 which may be sulfonated in this process I would mention benzene which is preferably sulfonated in a solvent comprising an excess of benzene, and naphthalene which may be sulfonated in benzene as a solvent or in a 85 solvent of the paraffin series, such as naphtha. Other solvents having the properties mentioned above will readily suggest themselves to those skilled in the art.

I shall describe my process in connection 90 with the sulfonation of benzene as an example, first taking up the process as it would be carried out in the apparatus illustrated by Fig. 1 and afterward as it would be carried out in the apparatus illustrated in 95 Fig. 2.

In starting the process with the apparatus illustrated in Fig. 1, the receptacle 1 may be partly filled with sulfuric acid, preferably fuming sulfuric acid, through inlet 2. 100 The aromatic hydrocarbon to be sulfonated for example benzene, is then run in under pressure through inlet pipe 3, either alone or dissolved in some solvent possessing the properties set forth, and the receptacle is 105 filled so that after reaction, the sulfonated product dissolved in an excess of the hydrocarbon itself or other suitable solvent runs

out through outlet pipe 4. By reason of its lower specific gravity than the sulfuric acid, the hydrocarbon to be sulfonated or the hydrocarbon and its solvent pass upward through the sulfuric acid and the hydrocarbon and sulfuric acid are thus brought into intimate contact and thoroughly commingled with each other, reacting upon each other to form the sulfonic acid of the aromatic hydrocarbon or derivative thereof, undergoing treatment, in the illustrated case benzene sulfonic acid.

As is more specifically set forth in U. S. Letters Patent Nos. 1,211,923 and 1,212,612 issued on January 9, 1917 and January 16, 1917, respectively, to Louis M. Dennis, the aromatic hydrocarbon such as benzene, if this is used alone, is introduced in excess and said excess over the amount reacting with the sulfuric acid, dissolves the resulting sulfonic acid from the mixture of sulfonic acid and sulfuric acid, extracting the same simultaneously with its formation, and carrying it out through the outlet pipe 4, the sulfonic acid being soluble in the said aromatic hydrocarbon while the sulfuric acid is not appreciably soluble therein. As the formation of the sulfonic acid takes place in an excess of the aromatic hydrocarbon, the absorption or extraction of the sulfonic acid is immediate and the efficiency of the Dennis process so far as extraction goes, is insured and increased.

The aromatic hydrocarbon either alone or dissolved in a suitable solvent may be continuously supplied to the receptacle and the spent or somewhat spent sulfuric acid continuously withdrawn from the receptacle through the outlet 5 while fresh sulfuric acid of proper strength may be continuously charged into the receptacle through inlet 2 so that the process of sulfonation and simultaneous extraction may be carried out as a continuous one or the supply of aromatic hydrocarbon or hydrocarbon dissolved in a suitable solvent may be continued until the acid becomes too weak to properly react in which case the supply of aromatic hydrocarbon or hydrocarbon dissolved in a suitable solvent may be cut off, the weak acid withdrawn and the receptacle charged afresh, in this instance the process being intermittent.

In the sulfonation of a hydrocarbon of the aromatic series in the apparatus shown in Fig. 2, as given in connection with the process carried out in the apparatus shown in Fig. 1, the tanks are all first filled with the aromatic hydrocarbon under pressure through pipe 17 and connecting pipes 18, 19, 20 and 21 (either alone or dissolved in a suitable solvent), until the hydrocarbon or hydrocarbon in solution begin to flow out at pipe 22. Sulfuric acid preferably fuming sulfuric acid, is then caused to enter tank 10

through pipe 11 and flows thence serially downward through tanks 9, 8, 7, and 6 by means of connecting pipes 12, 13, 14 and 15, respectively and out through pipe 16. The sulfuric acid, by reason of its greater density as compared with the aromatic hydrocarbon or hydrocarbon in solution flows downward through the respective tanks against the ascending current of the aromatic hydrocarbon or hydrocarbon in solution which, on the other hand, by reason of its lower density or specific gravity, passes upward serially through the tanks and out through the pipe 22. The hydrocarbon to be sulfonated and the sulfuric acid are thus brought in intimate contact and thoroughly commingled through the counter current flow and react upon each other to form the sulfonic acid of the aromatic hydrocarbon undergoing treatment with simultaneous extraction of the sulfonic acid from the residual sulfuric acid by the excess of the aromatic hydrocarbon present or by the solvent thereof. In this case, as in connection with the process described in connection with Fig. 1, the aromatic hydrocarbon may be introduced in excess or dissolved in a suitable solvent and said excess above the amount reacting with the sulfuric acid or said solvent dissolves the resulting sulfonic acid from the mixture of sulfonic acid and sulfuric acid extracting the same simultaneously with its formation and carrying it out through pipe 22, the residual sulfuric acid flowing out through pipe 16 accompanied by a small amount of sulfonic acid if the extraction is not complete.

By the process as practised in connection with the apparatus shown in Fig. 2, a continuous sulfonation of the hydrocarbon with simultaneous extraction of the sulfonic acid produced results, the hydrocarbon entering the apparatus at the lower end in excess or dissolved in a suitable solvent, and the sulfuric acid preferably fuming sulfuric acid, entering the apparatus at the upper end, the liquids flowing against each other on the counter current principle. A continuous stream of the aromatic hydrocarbon solution of the sulfonic acid produced or of the solvent and sulfonic acid flows out through pipe 22 for separation and further treatment, while a continuous stream of residual sulfuric acid flows out through pipe 16 to be used for any desired purpose. As is obvious, the purer hydrocarbon meets first with the less concentrated sulfuric acid and the more strongly sulfonated hydrocarbon meets with the more concentrated sulfuric acid in the usual counter-current way.

It is obvious that the number and arrangement of tanks and the manner of connection between them, may be varied to suit the conditions and that the process is applicable to the sulfonation of any aromatic hydrocar-

bon by either a continuous or an intermittent process which hydrocarbon or its solvent possesses the property of dissolving the sulfonic acid produced and not dissolving any appreciable amount of the sulfuric acid, and I do not restrict myself to any of the details hereinafter set forth nor to the sulfonation of any particular aromatic hydrocarbon further than the scope of the appended claims demands.

Wherein in the claims I refer to an aromatic hydrocarbon in which the sulfuric acid is not appreciably soluble or to an excess of aromatic hydrocarbon in which the sulfuric acid is not appreciably soluble or to extracting the sulfonation product in an excess of the aromatic hydrocarbon, I mean to include as well any other suitable solvent in which the aromatic hydrocarbon and the sulfonation product but not the sulfuric acid are soluble.

I claim.

1. A process for the simultaneous sulfonation of aromatic hydrocarbons or their derivatives and the extraction of the sulfonated product, consisting in causing sulfuric acid and the substance to be sulfonated to react upon each other in the presence of a solvent in which said substance and the sulfonated product are soluble but the sulfuric acid is not appreciably soluble and withdrawing the sulfonated product extracted in said solvent.

2. A process for the simultaneous sulfonation of aromatic hydrocarbons or their derivatives and the extraction of the sulfonated product, consisting in causing sulfuric acid and the substance to be sulfonated to react upon each other in the presence of an organic solvent in which said substance and the sulfonated product are soluble but the sulfuric acid is not appreciably soluble and withdrawing the sulfonated product extracted in said solvent.

3. A process for the simultaneous sulfonation of aromatic hydrocarbons or their derivatives and the extraction of the sulfonated product, consisting in causing sulfuric acid and the substance to be sulfonated to react upon each other in the presence of an organic solvent of lower specific gravity than that of the sulfuric acid at the strength used and in which the substance to be sulfonated and the sulfonated product are soluble while the sulfuric acid is not appreciably soluble, and withdrawing the sulfonated product extracted in said solvent.

4. A process for the simultaneous sulfonation of aromatic hydrocarbons or their derivatives and the extraction of the sulfonated product consisting in causing sulfuric acid and an aromatic hydrocarbon in which the sulfuric acid is not appreciably soluble to react upon each other in the presence of an excess of the aromatic hydrocarbon and

70 withdrawing the sulfonated product extracted in an excess of the aromatic hydrocarbon.

5. A process for the continuous sulfonation of aromatic hydrocarbons or their derivatives, with simultaneous extraction of the sulfonated product consisting in continuously passing an excess of an aromatic hydrocarbon in which sulfuric acid is not appreciably soluble through sulfuric acid 75 and continuously removing the extracted sulfonated product in an excess of the aromatic hydrocarbon.

6. A process for the continuous sulfonation of aromatic hydrocarbons or their derivatives with simultaneous extraction of the sulfonated product consisting in passing an excess of an aromatic hydrocarbon in which sulfuric acid is not appreciably soluble through sulfuric acid, continuously 80 85 withdrawing the extracted sulfonated product in an excess of the aromatic hydrocarbon and continuously withdrawing the spent acid.

7. A process for the continuous sulfonation of aromatic hydrocarbons or their derivatives consisting in causing sulfuric acid and an aromatic hydrocarbon in which sulfuric acid is not appreciably soluble to continuously flow against each other on the 90 95 counter-current principle in the presence of an excess of the aromatic hydrocarbon.

8. A process for the continuous sulfonation of aromatic hydrocarbons or their derivatives with simultaneous extraction of the sulfonated product, consisting in causing sulfuric acid and an aromatic hydrocarbon in which sulfuric acid is not appreciably soluble to continuously flow against each other on the counter-current principle 100 105 in the presence of an excess of the aromatic hydrocarbon and continuously removing the resulting sulfonic acid dissolved in said excess of the aromatic hydrocarbon.

9. A process for the continuous sulfonation of aromatic hydrocarbons or their derivatives with simultaneous extraction of the sulfonated product consisting in passing a continuous flow of the aromatic hydrocarbon against a continuous flow of sulfuric 110 115 acid in the presence of an excess of the aromatic hydrocarbon and continuously separating the resulting sulfonic acid from the residual sulfuric acid.

10. A process for the simultaneous sulfonation of benzene and the extraction of benzene sulfonic acid consisting in causing sulfuric acid and benzene to react upon each other in the presence of an excess of benzene and withdrawing the benzene sulfonic acid 120 125 extracted in said excess.

11. A process for the continuous sulfonation of benzene with simultaneous extraction of benzene sulfonic acid consisting in continuously passing an excess of benzene 130

through sulfuric acid and continuously removing the extracted benzene sulfonic acid in said excess.

12. A process for the continuous sulfonation of benzene with simultaneous extraction of benzene sulfonic acid consisting in passing an excess of benzene through sulfuric acid, continuously withdrawing the extracted benzene sulfonic acid in said excess and continuously withdrawing the spent sulfuric acid.

13. A process for the continuous sulfonation of benzene with simultaneous extraction of benzene sulfonic acid consisting in causing sulfuric acid and benzene to continuously flow against each other on the counter-current principle in the presence of an excess of benzene.

14. A process for the continuous sulfonation of benzene with simultaneous ex-

traction of benzene sulfonic acid consisting in causing sulfuric acid and benzene to continuously flow against each other on the counter-current principle in the presence of an excess of benzene and continuously removing the benzene sulfonic acid in the excess of benzene.

15. A process for the continuous sulfonation of benzene with simultaneous extraction of benzene sulfonic acid consisting in passing a continuous flow of benzene against a continuous flow of sulfuric acid in the presence of an excess of benzene and continuously separating the resulting benzene sulfonic acid from the residual sulfuric acid.

In testimony whereof I have signed this specification.

HANS BULL.
